TILED WALL AND TILE THEREFOR

Charles J. Stanley, Chicago, Ill., and John T. Welch, Dowagiac, Mich.

Application January 27, 1939, Serial No. 253,044

15 Claims. (Cl. 72—19)

This invention relates to improvements in tiled wall and tile therefor.

The main objects of this invention are:

5 First, to provide a tiled wall which is well adapted for use in atmospheres of high humidity and where it is necessary to frequently wash or clean the wall.

10 Second, to provide a tiled wall which may be very economically produced both in the matter of labor and material.

15 Third, to provide an improved tile which is very economical and at the same time may be produced in a very great range of colors and is very durable.

20 Objects relating to details and economies of the invention will appear from the description to follow. The invention is defined and pointed out in the claims.

25 A preferred embodiment of the invention is illustrated in the accompanying drawing, in which:

Fig. 1 is a fragmentary elevation illustrating the foundation and the improved tile in its relation to the foundation or the improved wall structure.

30 Fig. 2 is a rear view of the embodiment illustrated of the improved tile, the fasteners being conventionally shown.

Fig. 3 is a fragmentary section on a line corresponding to line 3—3 of Figs. 1 and 2.

35 Fig. 4 is an enlarged fragmentary inverted perspective view of the face plate or panel of the tile.

Fig. 5 is an enlarged fragmentary view of the body or backing for the tile.

40 Referring to the drawing, 1 is the foundation panel for supporting the tile, this foundation being preferably formed of waterproof composition or fiberboard and is secured to the studding 2 or other suitable support. The waterproofing is of substantial importance in securing a wall which is adapted for use in dairy stores, shower stalls, bathrooms, and the like where the walls are subject to substantial moisture.

45 The foundation is provided with a plurality of rows of holes 3 arranged in transverse alignment and uniformly spaced, the holes being uniformly spaced relative to each other and in this embodiment in groups of four throughout the main body or foundation.

50 The improved tile comprises face plates or panels 4 which may be square or of other desired configuration, depending upon the shape, size or disposition of the surface to be covered and also as to the tile design. These face plates are, in the embodiment illustrated, molded of artificial 55 or urea formaldehyde groups and have rearwardly

projecting edge or border flanges 5 which serve to stiffen the relatively thin face portion of the plate and also provide retaining means for the backing.

5 The flanges are provided with undercut or inwardly beveled lugs 6 at spaced intervals adapted as retaining parts or members for the backing.

10 For convenience in manufacture and assembling, the backing of the embodiment illustrated is made up of outer sections 7 and an intermediate or key section 8, the outer sections having beveled edges 9 engageable with the undercut lugs 6 by a lateral sliding movement of the sections 7. The section 8 which is in effect a key section is arranged between the sections 7 and locks them in engagement with the retaining lugs.

15 Strips of adhesive tape 10 arranged over the joints between the sections 7 and 8 retain the section 8 in position. These backing sections are also formed of waterproofed fiberboard.

20 To secure the tile in position upon the foundation, I provide a plurality of rotatable drive screw fasteners 11, these fasteners being secured to the tile backing by means of clips 12 which are seated in recesses 13 provided therefor in the backing members 7 or the backing members which have interlocking engagement with the face plate of the tile.

25 The clips 12 have holes 14 receiving the fasteners 11, the heads of the fasteners being arranged on the inner sides of the clips. The clips are provided with fastening prongs 15 which are clinched in the backing members as indicated at 16 thereby rotatably securing the fasteners to the tile.

30 The holes 3 of the foundation and the fasteners are spaced to correspond or so that in assembling the tile upon the foundation, the tile may be secured merely by registering the fasteners with the holes and forcing or driving them into the holes of the foundation.

35 The backing preferably projects somewhat to the rear of the edges of the flanges of the face plate as shown in Fig. 3 which permits the plastic joint filler 17 filling into the rear of the flanges. This joint material is not relied upon to secure the tile in place but it does serve to prevent the entrance of moisture and also it gives the appearance of a cement mounted tile.

40 The adhesive strips 10 serve as an effective means for holding the sectional backing members in position and does not prevent the tile lying flat against the foundation.

45 The improved tile is very inexpensive both in the matter of material and assembly of the tile and the mounting of the tile on the wall may be done by relatively inexperienced workmen. While 50

the face plates of the tile are preferably formed of molded plastic, certain features of the invention are adaptable to face plates formed of other materials. Molded plastic, however, has very great advantages in that it can be produced in a great variety of colors and the colors may be accordingly matched should occasion for replacement be required and the individual tile as well as the wall itself is very attractive. It is not affected by moisture.

10 We have illustrated and described our improvements in an embodiment which we consider highly practical. We have not attempted to illustrate or describe other embodiments which 15 we contemplate as we believe this disclosure will enable those skilled in the art to embody or adapt our improvements as may be desired.

Having thus described our invention, what we 20 claim as new and desire to secure by Letters Patent, is:

25 1. A wall structure comprising a foundation of waterproof fiberboard having a plurality of spaced rows of holes, a plurality of tile each comprising a face plate having inturned flanges at its edges provided with spaced lugs having inwardly beveled faces, complementary backing sections for said face plate, certain of said sections having beveled edges in interlocking engagement with said lugs and engageable therewith by lateral sliding movement of the sections within the face plate flanges, and an intermediate key section disposed between the sections in engagement with said lugs, said sections engaged with said lugs being provided with 30 drive fasteners spaced for engagement with said holes in said foundation.

40 2. A wall structure comprising a foundation of waterproof fiberboard having a plurality of spaced rows of holes, a plurality of tile each comprising a face plate of artificial resin having inturned flanges at its edges provided with spaced lugs having inwardly beveled faces, complementary backing sections for said face plate, certain of said sections having beveled edges in interlocking engagement with said lugs and engageable therewith by lateral sliding movement of the sections within the face plate flanges, and an intermediate key section disposed between the sections in engagement with said lugs, said sections engaged with said lugs being provided with 45 fasteners spaced for engagement with said holes in said foundation.

45 3. A wall structure comprising a foundation of waterproof fiberboard having a plurality of spaced rows of holes, a plurality of tile each comprising a face plate having inturned flanges at its edges provided with spaced undercut backing engaging parts, complementary backing sections for said face plate, certain of which are in interlocking engagement with said backing engaging parts, such sections being engageable with such parts by lateral sliding movement of the sections, and a key section disposed between the sections in engagement with said retaining parts 50 and secured in position therebetween, said sections engaged with said retaining parts being provided with rotatable drive fasteners spaced for interlocking engagement in said holes in said foundation.

55 4. A tile comprising a face plate having inturned flanges at its edges provided with spaced lugs having inwardly beveled faces, complementary backing sections for said face plate, certain of said sections having beveled edges in 60 interlocking engagement with said lugs and en-

gageable therewith by lateral sliding movement of the sections within the face plate flanges, and an intermediate key section disposed between the sections in engagement with said lugs and retained in position by adhesive joint lapping strips, 5 said sections engaged with said lugs being provided with foundation engaging elements.

5. A tile comprising a face panel having inturned flanges in its edges provided with spaced undercut portions, a backing comprising a plurality of complementary sections, certain of said sections being in interlocking engagement with said undercut portions and engageable and disengageable therefrom by a lateral sliding movement within the panel flanges, and an intermediate key section disposed between the sections in engagement with said lugs and secured in position therebetween for preventing lateral lug disengaging movement thereof, said sections engaged with said undercut portions being provided with recesses in their rear faces, drive fastening members, and retaining clips therefor disposed in said recesses and provided with prongs engaging said backing sections.

6. A tile comprising a face panel having inturned flanges in its edges provided with spaced undercut lugs, a backing comprising a plurality of complementary sections, certain of said sections being in interlocking engagement with said lugs and engageable and disengageable therefrom by a lateral sliding movement within the panel flanges, and an intermediate key section disposed between the sections in engagement with said lugs and secured in position therebetween for preventing lateral lug disengaging movement thereof, said lug engaging sections being provided with rotatable drive screw fasteners.

7. A tile comprising a face panel of artificial resin having inturned flanges in its edges provided with spaced undercut lugs, a backing comprising a plurality of complementary sections, 40 certain of said sections being in interlocking engagement with said lugs and engageable and disengageable therefrom by a lateral sliding movement within the panel flanges, and an intermediate key section disposed between the sections in engagement with said lugs and secured in position therebetween for preventing lateral lug disengaging movement thereof, said lug engaging sections being provided with support engaging members.

8. A tile comprising a face panel having undercut portions on its rear face, backing sections engageable with said undercut portions by a lateral sliding movement, and a key backing section arranged between the backing sections engaged with said undercut portions and secured in position therebetween by means of adhesive strips overlapping the joints of the sections.

9. A tile comprising a face panel having undercut portions on its rear face, backing sections engageable with said undercut portions by a lateral sliding movement, and a key backing section arranged between the backing sections engaged with said undercut portions and secured in position therebetween.

10. A tile comprising a face panel provided with rearwardly directed edge flanges having backing retaining portions, backing sections engageable with the said retaining portions by a lateral sliding movement of said backing sections, means for securing said sections in their engaged position, and tile supporting members carried by said engaged sections.

11. A tile comprising a face panel of artificial

- resin and having integral backing engaging and retaining members on the rear side thereof, a backing comprising a plurality of sections, certain of which are engaged with said retaining members and another thereof coacting with the retaining member engaging sections to serve as a key member, means for retaining the key member section in position, and drive fastenings mounted on the retaining member engaging sections.
- 5 12. A tile comprising a face panel, a backing member therefor having a recess in its rear face, a headed drive fastener, and a retaining clip for said fastener through which said drive fastener is arranged seated in said recess and provided with retaining prongs in clinched engagement with the backing member whereby the drive fastener is supported to permit rotative movement thereof.
- 10 13. A tile comprising a face panel of artificial resin and having backing engaging members on the rear side thereof, a backing comprising a plu-

rality of sections, certain of which are engaged with said retaining members, another section coacting therewith to serve as a key member, and means for retaining the key member section in position.

14. A tile comprising a face panel, a backing member therefor, a headed drive fastener, and a retaining clip for said fastener through which said drive fastener is arranged, said clip having retaining prongs in clinched engagement with the backing member whereby the drive fastener is supported to permit rotative movement thereof.

15. A tile comprising a backing of fibrous material provided with a plurality of inwardly opening recesses, headed fastener members, and retainers for said fastener members seated in said recesses and provided with prongs penetrating said backing and having clinched engagement therewith.
